UNITED STATES PATENT OFFICE

JOSEPH SCHULMAN, OF BROOKLYN, NEW YORK

DESIGN FOR A FENDER

Application filed November 15, 1929. Serial No. 33,463. Term of patent 14 years.

To all whom it may concern:

Be it known that I, JOSEPH SCHULMAN, a citizen of the United States, and residing in the county of Kings, city of Brooklyn, and State of New York, have invented a new, original, and ornamental Design for a Fender, of which the following is a specification, reference being had to the accompanying drawings, forming a part thereof.

Figure 1 is a view in side elevation of a fender showing my new design; and

Figure 2 is a transverse sectional view on the line 2—2 of Figure 1, looking in the direction of the arrows, and showing, at the

left, the downwardly extending flange which hides the spare tire receiving well and conforms in longitudinal contour therewith.

Figure 3 is a fragmentary view showing that portion of the fender containing the fender well and looking in a direction perpendicular to the top face of the fender.

I claim:

The ornamental design for an automobile fender as shown and described.

This specification signed this 13th day of November, 1929.

JOSEPH SCHULMAN.
